Filed June 29, 1970, Ser. No. 23,751

Term of patent 14 years

Int. Cl. D15—08

U.S. Cl. D55—1

FIG. 2

FIG. 1

FIG. 1 is an elevational side view of the rack for collecting and dispensing liquid showing my design;

FIG. 2 is an elevational side view similar to FIG. 1, but showing the cover of the rack in an elevated position and on an enlarged scale;

FIG. 3 is an elevational view upon the side of the rack opposite to the one shown in FIGS. 1 and 2, the cover of the rack being removed for convenience of illustration;

FIG. 4 is an elevational side view similar to FIG. 3, but turned through an angle of 90°;

FIG. 5 is a top view of FIG. 3; and
FIG. 6 is a bottom view of FIG. 3.

I claim:

The ornamental design for a rack for collecting and dispensing liquid, as shown and described.
